COMBINED TELEVISION AND STEREO
CABINET OR SIMILAR ARTICLE

Frank Propps, 1355 E. 14th, Des Moines, Iowa 50316

Filed Mar. 27, 1967, Ser. No. 6,394

Term of patent 3½ years

(Cl. D56—4)

Fig. 1

Fig. 2

Fig. 3

Fig. 4

4

FIGURE 1 is a top plan view of a combined television and stereo cabinet or similar article showing my new design;

FIGURE 2 is a front elevational view thereof;

FIGURE 3 is an end elevational view thereof as viewed from the right-hand end of FIGURE 2; and

FIGURE 4 is a fragmentary cross-sectional view thereof as viewed on line 4—4 of FIGURE 2.

Portions of FIG. 2 are diagonally lined to indicate transparency. The dominant features of my new design are shown in the solid lines of the drawing.

I claim:

The ornamental design for a combined television and stereo cabinet or similar article, substantially as shown and described.
